UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Original application filed May 17, 1922, Serial No. 561,603. Divided and this application filed March 14, 1923. Serial No. 624,930.

To all whom it may concern:

Be it known that I, HAROLD G. WARR, a citizen of the United States, residing at Park Ridge, in the county of Cook and

5 State of Illinois, have invented certain new and useful Improvements in Rail Anchors, of which the following is a specification.

My invention relates to rail anchoring devices adapted to resist the tendency of rail-10 road rails to creep longitudinally.

One of the objects of the invention is to provide an improved one-piece rail anchor which may be easily applied to or removed from the flange of a rail without danger 15 of subjecting the anchor to excessive strains, and which will be maintained in its applied position by spring pressure of the anchor.

A specific object of the invention is the provision of a rail anchor having a jaw 20 adapted to be driven into tight engagement with one flange of the rail base, and having a body which extends under the rail base and engages the other edge thereof, the body being provided with a relatively flexible portion adapted to flex downwardly 25 during the application of the anchor to the rail so as to relieve the jaw portion of the anchor of excessive strains.

A more specific object of the invention is 20 the provision of a rail anchor of the above character that can be conveniently manufactured of sheet metal so as to provide one or more relatively rigid jaw portions adapted to engage one edge of a rail base, and a 35 somewhat resilient portion adapted to extend under the rail base and bear with resilient pressure against the other edge of the rail base.

A further object of the invention is the 40 provision of an anchor device having a relatively rigid jaw and a spring tongue for engaging opposite edges of a rail, and to so form the anchor that the engagement of this jaw and tongue with the rail will be confined 45 to portions adjacent opposite edges of the rail base.

The invention further consists in such other new and improved constructions relating to rail anchors as will be hereafter de-

scribed and claimed for carrying out the 50 above stated objects, and such other objects as will appear from the following description.

The invention is illustrated in certain preferred embodiments in the accompanying 60 drawing, wherein like characters of reference designate corresponding parts throughout the several figures thereof, and wherein—

Fig. 1 is a front view in elevation of a 60 rail anchor device constructed in accordance with my invention, shown applied to the base flange of a rail, said base flange of the rail being shown in cross-section;

Fig. 2 is a plan view of the structure 65 shown in Fig. 1.

Fig. 3 is a front view, partly in elevation and partly in section, of a modified form of rail anchor constructed in accordance with 70 my invention; and

Fig. 4 is a view in perspective of the modified construction shown in Fig. 3, the base flange of the rail being omitted in this figure.

Referring first to Figs. 1 and 2 of the 75 drawing: 10 designates the base portion of a railway rail and 11 one of the cross-ties on which the rail is supported.

My improved anchor, as shown in Figs. 1 and 2 of the drawing is made of sheet 80 metal, preferably spring steel, and is formed at one end with a hook-shaped jaw portion 12 which engages the vertical and both the upper and lower surfaces of the rail base at one side of the rail, and at the other end 85 with an upstanding lug or shoulder 13 adapted to engage the vertical surface of the rail base at the other side of the rail. The jaw portion 12 is provided with a lip 14 which projects over and bears against the 90 upper inclined surface of the rail base, the lower edge 15 of the lip being cut at an angle corresponding to the inclination of the upper surface of the base flange of the rail. The lower edge of the lip 14 is provided 95 with a recess 16 so as to prevent engagement of the lip with the upper corner of the rail base, thereby insuring against the possibility

of so flexing the jaw, during the application of the anchor to a rail, as to move the end portion of the lip out of contact with the rail. By forming the lip 14 with the recess 16, the jaw may be made relatively rigid yet possessed of sufficient resiliency to permit its application to rails made within the allowable variation in thickness of their base flanges without subjecting the jaw to excessive distortion. The vertical edge 17 of the jaw preferably, though not necessarily, engages the vertical surface of the rail base.

In order to minimize the flexing of the jaw portion during the application of the anchor to a rail, and to relieve it of the severe strains incident to such flexing, I preferably make the shoulder 13 relatively short and decrease the width of the body 18 toward the shoulder 13, so that the portion 20 of the body adjacent the shoulder 13 will be more flexible than the portion of the body adjacent the jaw end of the anchor. With this construction, the body portion will flex on a horizontal axis when the jaw 25 12 is driven to its rail-gripping position. As soon as the shoulder 13 clears the other edge of the rail base, it will snap into the position shown in Fig. 1.

The upper edge of the body 18 is preferably recessed, as indicated at 19, so as to avoid improper engagement of the anchor with the rail in the event that the bottom surface of the rail is formed with rough or uneven surface at the point where the anchor is applied. The relatively wide portion 25 of the body adjacent the jaw end 12 provides a suitable tie abutting surface.

In applying the anchor to a rail, the jaw portion is hooked over one edge of the rail base and the anchor then driven in the direction of its length across the rail until the shoulder 13 snaps over the opposite edge of the rail base. In the various positions assumed by the anchor during the application to the rail until the shoulder 13 snaps over the opposite edge of the rail base, the narrowest portion of the body, being of greater flexibility than the jaw portion of the anchor, will flex downwardly and thereby minimize the flexing strain on the jaw portion of the anchor.

In Figs. 3 and 4, I have shown a modified form of the invention made from a sheet metal blank cut and bent to the form shown in Fig. 4. This embodiment of the invention consists of a flat body portion 20 adapted to extend across the rail base, and is formed at one end with two relatively rigid upstanding jaw portions 21, 22, having recesses 23 which receive one edge of the rail base. The jaw members 21 and 22 are adapted to be driven to a tight gripping contact with the upper and lower surfaces of the rail base, and the body portion 20 is adapted

to function as a spring tongue to maintain the device in its applied position. The body portion is preferably bent upwardly toward the rail and bears against the under surface of the rail near one edge thereof, thereby providing a space between the bottom surface of the rail base and the body portion of the anchor which will prevent rough or uneven portions of the rail base interfering with the proper application of the anchor. The body portion decreases in width 75 towards one end, so as to make it more flexible at this end, and is provided with an upstanding lip 24 which by reason of the resiliency of the body of the anchor snaps over the opposite edge of the rail base when 80 the anchor is driven home. When the anchor is in its applied position, one of the upstanding jaw portions 21 or 22, as the case may be, will be in position to bear against an adjacent cross-tie. By decreasing the 85 width of the body portion 20, the end of the anchor adjacent the lip 24 is held out of engagement with the tie, thereby permitting the anchor to assume a slight diagonal position across the rail base, if such position be necessary to take up any clearance 90 between the lip 24 and the vertical edges 25, 25, of the jaw portions 21, 22.

This application is a division of my co-pending application Serial No. 561,603, filed 95 May 17, 1922. The invention generic to the two applications is claimed in the parent case No. 561,603 and not herein.

I claim:

1. A rail anchor comprising a sheet metal member provided at one end with a jaw portion for engaging one edge of a rail base, and at the other end with means for engaging the other edge of said rail base; a portion of the member intermediate said jaw and said means being resilient and adapted 100 to be flexed downwardly during the application of the anchor to a rail.

2. A rail anchor comprising a sheet metal member provided at one end with a substantially rigid jaw portion for engaging one edge of a rail base and at the other end with means for engaging the other edge of said rail base; a portion of the member intermediate said jaw and said means being 110 resilient and adapted to be flexed downwardly during the application of the anchor to a rail.

3. A one-piece rail anchor comprising a sheet metal member recessed at one end to provide a jaw for engaging one edge of a rail base and formed at the other end with means for engaging the other edge of said rail base; a portion of the member intermediate said jaw and said means being resilient and adapted to be flexed downwardly 115 during the application of the anchor to a rail.

4. A rail anchor comprising a sheet metal

- member recessed at one end to provide a substantially rigid jaw for engaging one edge of a rail base, and provided at the other end with a shoulder for engaging the other edge of said rail base; a portion of the member intermediate said jaw and shoulder being resilient and adapted to be flexed downwardly during the application of the anchor to a rail.
10. A rail anchor comprising a sheet metal member formed at one end with a substantially flat jaw portion adapted to be normally disposed edgewise with relation to the base of the rail and engage the upper and lower surfaces of said base at one side of the rail, and formed at the other end with a shoulder for engaging the other side of said base; a portion of said member intermediate said jaw and shoulder being resilient and adapted to be flexed downwardly during the application of the anchor to a rail.
15. A rail anchor comprising a sheet metal member formed at one end with a substantially flat jaw portion adapted to be normally disposed edgewise with relation to the base of a rail and engage the upper and lower surfaces and the vertical edge of said base at one side of the rail, and formed at the other end with a shoulder for engaging the other side of said base; a portion of said member intermediate said jaw and shoulder being resilient and adapted to be flexed downwardly during the application of the anchor to a rail.
20. A rail anchor comprising a sheet metal member formed at one end with a substantially flat jaw portion adapted to be normally disposed edgewise with relation to the base of a rail and engage the upper and lower surfaces and the vertical edge of said base at one side of the rail, and formed at the other end with a shoulder for engaging the other side of said base, the portion intermediate said jaw and shoulder decreasing in cross-sectional area towards said abutment to increase the flexibility of said member.
25. A rail anchor comprising a body formed at one end with a jaw portion which engages the upper surface and vertical edge of a rail base and formed at the other end with an abutment for engaging the opposite edge of the rail base, said body being formed to flex downwardly during the application of the device to a rail.
30. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
35. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
40. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
45. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
50. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
55. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
60. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
65. A rail anchor comprising a sheet metal member intermediate said jaw and the opposite end of said member being tapered in width to increase its flexibility.
70. A rail anchor comprising a sheet metal member formed at one end with a substantially flat jaw portion adapted to be normally disposed edgewise with relation to the base of a rail and engage the upper and lower surfaces thereof, and formed at the other end with a shoulder for engaging the other edge of said base; the portion of said member intermediate said jaw and said shoulder being tapered in width toward one end of said member to increase its flexibility.
75. A rail anchor comprising a sheet metal member formed at one end with a substantially rigid jaw for engaging one edge of a rail base, and provided at the other end with a shoulder for engaging the opposite edge of said base, the portion intermediate said jaw and shoulder decreasing in cross-sectional area towards said abutment to increase the flexibility of said member.
80. A rail anchor comprising a body formed at one end with a jaw portion which engages the upper surface and vertical edge of a rail base and formed at the other end with an abutment for engaging the opposite edge of the rail base, said body being formed to flex downwardly during the application of the device to a rail.
85. A rail anchor comprising a body formed at one end with a jaw portion which engages the upper surface and vertical edge of a rail base, and formed at the other end with an abutment for the opposite edge of the rail base, said body decreasing in width towards said abutment and adapted to flex to relieve said jaw of excessive strains during the application of the device to a rail.
90. A rail anchor made of sheet metal comprising a body formed at one end with a jaw portion which engages the upper surface and vertical edge of a rail base, and formed at the other end with an abutment for the opposite edge of the rail base; said body decreasing in width toward said abutment and adapted to flex to relieve said jaw of excessive strains during the application of the device to a rail and adapted to engage a small portion only of the under surface of said rail base for the purpose described.
95. A rail anchor made of sheet metal formed at one end with spaced upstanding jaw portions adapted to engage one edge of a rail base, and formed at the other end with an upstanding portion adapted to engage the other edge of said rail base; said body portion being arranged to bear with its flat side against the under surface of the rail base, and adapted to be flexed during the application of the device to a rail.

16. A rail anchor made of sheet metal formed at one end with spaced upstanding jaw portions adapted to engage one edge of a rail base, and formed at the other end 5 with an upstanding portion adapted to engage the other edge of said rail base, said body portion being arranged to bear with

its flat side against the under surface of the rail base and adapted to be flexed during the application of the device to a rail, and the 10 upstanding jaw portion adjacent the tie being adapted to bear against the vertical face of said tie.

HAROLD G. WARR.
